PISTON

Jack H. Davis, Dallas, Tex.

Application March 2, 1936, Serial No. 66,723

2 Claims. (Cl. 309—36)

This invention relates to an improved piston construction, having more particular reference to a type which is ideally and peculiarly adaptable and useful in slush pumps such as are used 5 to maintain the circulation of flushing fluids in well drilling operations.

In the perfection and development of piston constructions in this particular classification, considerable thought has been given to the idea of 10 promoting longevity while retaining an effective seal even over a prolonged period of operation. Along the line of the present invention to be hereinafter described in detail, it may be said that the art includes a sectional head construction embodying expanding and contracting means 15 or elements cooperable with an interposed radially expansible and contractible packing annulus.

It is in the foregoing particular field of improvement in which I have worked and finally 20 developed what is believed to be a comparatively new and structurally distinct adaptation characterized in one sense by a radially expansible and contractible rubber annulus or packing ring, 25 wherein means is located between the coordinated surfaces of the ring and the clamping and adjusting parts to provide a substantially fluid-proof seal.

Novelty is also predicated, as will be herein- 30 after clarified, on an ingenious structural arrangement characterized by the companion metallic parts forming the sectional mounting and clamping means for the rubber annulus wherein these parts are designed for respective adjust- 35 ment to obtain more effective and lasting adjusting and sealing results.

Other features and advantages will become 40 more readily apparent from the following description and the accompanying illustrative drawings.

In the drawings:

Figure 1 is a side elevational view disclosing 45 the appearance, externally, of the improved and structurally refined piston or plunger head.

Figure 2 is a view partly in section and partly 50 in elevation disclosing with greater particularity the details and coordinated assemblage depicted in Figure 1.

Figure 3 is an end view of Figure 1 observing 55 it in a direction from left to right.

Figure 4 is an inside elevational or face view of 60 the nut adjusted flanged collar or compressing and follower disk.

Figure 5 is a sectional view disclosing the two

units which go to make up the rubber packing mounting and clamping assembly.

Figure 6 is a fragmentary end view of the multiple annular grooved rubber packing ring.

Figure 7 is a perspective view of a shim constituting a part of the assembly as disclosed in 5 Figure 2.

As shown better in Figure 2, the reciprocatory piston rod is denoted by the numeral 8 and is formed with a beveled shoulder 9 merging into 10 a reduced extension whose inner end is smooth to provide an adapter stem as indicated at 10 and whose outer end is screw-threaded as indicated at 11 to provide a requisite shank to accommodate the clamping nut 12 and the lock 15 nut 13.

The rubber annulus or packing ring or member is indicated by the numeral 13 and is of somewhat conventional annular expansible and contractible form. It is here shown, however, as 20 being provided at its opposite ends with substantially conical cavities 15 in turn provided with concentric graduated grooves. There are three grooves, the inner and outer ones being relatively shallow and denoted by the numerals 16 and 17, 25 and the intervening or central one being somewhat deeper and differentiated by the numeral 18. In addition, I provide peripheral circumferentially extending spaced parallel grooves 19 and 20 which are disposed in somewhat inwardly 30 converging relationship as compared to each other. This provides for freedom of compression and expansion on the periphery not generally found in the marginal construction of such packing rings.

The annulus is supported on or accommodated 35 by a two-part assemblage which may be conveniently defined as a mounting or hub structure. The relatively stationary unit is denoted by the numeral 21 and the companion relatively 40 movable follower unit is indicated at 22. The casting 21 comprises a cylindrical open-ended sleeve or hub proper 23 which surrounds the smooth stem portion 10 of the piston rod. At the right hand end is a beveled shoulder 24 intimately cooperating with the beveled shoulder 9 to provide an effective complementary joint. Adjacent this same end is a disk-like flange 25 of a diameter less than the diameter of the cavity 15 into which it fits. The entire inner face of 50 the flange is beveled radially inward or outward, as the case may be, to form a sort of a conical clamping surface to cooperate with the correspondingly shaped surface of the cavity 15. Incidentally, on this surface I provide integral an- 55

nular ribs or beads 16^a, 17^a, and 18^a which features cooperate with the grooves 16, 17, and 18, in the rubber. The relatively long central bead fits into the correspondingly deep groove 18.

5 5 These features come together in proper matching relation to provide requisite coacting means calculated to form a fluid tight seal or joint between the conical flange 25 and the conical surface of the complementary cavity 15.

10 10 The relatively slideable clamping and take-up collar or follower unit 22 is also in the nature of a disk 26 corresponding to the cavity and having the same taper as on the part 25. It is also formed with corresponding ribs to fit into the 15 15 corresponding grooves in the rubber. Hence, the same numerals designate the same parts. It is to be noted that the collar portion 27 is screw-threaded as at 28, to provide a feed nut. In addition, it is fashioned with a socket 29 to telescopically receive the left hand end of the cylindrical hub member or sleeve 23. Located in the space between the bottom of the socket and the end of the hub are the shims 30. A suitable 20 20 number of shims is introduced at the initial installation and the number of shims is gradually reduced as wear takes place and as it becomes necessary to feed the follower unit 22 into binding or clamping contact with the expansible and contractible rubber annulus 14. By providing the 25 25 bead and groove sealing means between the flanges and cavities, it is evident that the liquid cannot feed between the parts and enter the socket containing the variable shims 30.

30 30 As before indicated, novelty is predicated upon the parts separately and collectively, and especially upon the effectiveness brought about by the special adaptation and coordination thereof.

It is thought that the description taken in connection with the drawings will enable a clear understanding of the invention to be had. Therefore, a more lengthy description is thought unnecessary.

5 5 While the preferred embodiment of the invention has been shown and described, it is to be understood that minor changes coming within the field of invention claimed may be resorted to if desired.

10 10 I claim:

1. As a new product of manufacture and as a component part of a structure of the class described, an annular compressible rubber packing ring, said ring being provided with a pair of 15 15 converging peripheral grooves and having conical cavities formed in its opposite ends, said cavities being provided with concentric radially spaced grooves in the manner and for the purposes described.

2. A pump piston comprising a piston rod, a pair of telescoping hub members mounted on the rod, said hub members including flanges having bevelled opposed faces, a plurality of annular ribs formed on opposed faces of the flanges, 25 25 an annular compressible rubber packing ring positioned between said flanges and having inclined ends corresponding to the bevelled faces of the flanges and also having annular grooves in its ends to accommodate the ribs on the flanges, 30 30 said ring being of greater diameter than the flange and a plurality of circumferential grooves formed on the peripheral edge of the ring having their walls inclined toward each other to provide a plurality of packing surfaces on the ring and to facilitate expansion thereof.

35 35 JACK H. DAVIS.
